MERCHANDISE DISPLAY DEVICE

Billy Moretini, Chicago, Ill., assignor to International
Design Corporation, Chicago, Ill.

Filed Oct. 27, 1971, Ser. No. 193,231

Term of patent 14 years

Int. Cl. D6—04

U.S. Cl. D6—24

FIG. 1

FIG. 2

FIG. 3

FIG. 4

FIG. 5

FIG. 6

FIG. 7

FIG. 8

FIG. 1 is a perspective view of a merchandise display device illustrating my new design;

FIG. 2 is a front elevational view thereof;

FIG. 3 is a rear elevational view thereof;

FIG. 4 is a top plan view thereof;

FIG. 5 is a top plan view of the base of the device with the shelf units and supporting standard removed;

FIG. 6 is a perspective view of a shelf unit with a portion of the shelf surface removed for clarity of illustration;

FIG. 7 is a side elevational view of a merchandise display device illustrating my new design with the shelf units axially aligned; and

FIG. 8 is a side elevational view of a merchandise display device illustrating my new design with an additional shelf unit, and with the shelf units in opposite axial alignment.

I claim:

The ornamental design for a merchandise display device, as shown and described.
